UNITED STATES PATENT OFFICE.

GEORGE H. GIBSON, OF MONTCLAIR, NEW JERSEY, AND PAUL A. BANCEL, OF NEW YORK, N. Y.

STEAM-CONDENSING APPARATUS.

1,143,382.

Specification of Letters Patent. Patented June 15, 1915.

Application filed November 29, 1912. Serial No. 733,941.

To all whom it may concern:

Be it known that we, GEORGE H. GIBSON, of Montclair, in the county of Essex and State of New Jersey, and PAUL A. BANCEL, 5 of the city and county of New York, in the State of New York, both citizens of the United States, have invented a certain new and useful Improvement in Steam-Condensing Apparatus, of which the following 10 is a true and exact description, reference being had to the accompanying drawings, which form a part thereof.

Our present invention relates to apparatus, such as is employed for condensing the 15 exhaust steam from steam turbines, engines or the like, and particularly to condensing apparatus of the type in which there is employed a main condenser with separate outlets for water of condensation and air, and 20 in conjunction therewith an auxiliary condensing and vacuum producing apparatus for withdrawing air from the main condenser and for condensing the steam admixed therewith. By the term "air" as 25 used in this connection, we mean to include not only atmospheric air but all other gases and vapors not readily condensable and tending to accumulate in the condensing space of the main condenser or other chamber to be 30 exhausted.

The object of the present invention is to provide improved means for withdrawing the air from a main condenser or other vacuum chamber, and in particular to provide 35 for the maintenance of a high vacuum in the main condenser or other vacuum chamber with a vacuum pump of less capacity and less expensive to manufacture than has heretofore been required. In accomplishing this result we utilize the steam 40 supplied to an auxiliary turbine, employed to drive the air or water circulating pump or like power consuming device pertaining to the plant of which the apparatus forms a 45 part. We utilize this steam by first expanding it to the low pressure which it is desired to maintain in the main condenser or other vacuum chamber and employing the jet action of the expanded steam to suck the 50 air and steam admixed therewith in larger or smaller amount, out of the main condenser or other vacuum chamber, and to carry the resulting mixture through a re-compression nozzle in which the mixture is 55 compressed to a pressure somewhat above

the vacuum maintained in the main condenser or other vacuum chamber, prior to its delivery to the auxiliary condenser and vacuum producing apparatus. The resulting decrease in vacuum which it is necessary 60 to maintain in the auxiliary apparatus decreases the required capacity and increases the efficiency of the latter. A portion of the kinetic energy of the steam developed by its expansion is imparted to the turbine 65 through which the steam or the mixture of air and steam is passed prior to its delivery to the auxiliary condensing apparatus.

The various features of novelty which characterize our invention are pointed out 70 with particularity in the claims annexed to and forming a part of this specification. For a better understanding of our invention, however, and the advantages possessed by it, reference may be had to the accompanying 75 drawings and descriptive matter, in which we have illustrated and described various embodiments of our invention.

Of the drawings: Figure 1 is a diagrammatic representation, partly in sectional 80 plan, of one form of apparatus embodying our invention. Fig. 2 is a partial sectional plan of a portion of a modified form of apparatus. Fig. 3 is a sectional plan of a portion of another modified form of apparatus; and Fig. 4 is a section on the line 4-4 of Fig. 3.

In the drawings, and referring first to the construction shown in Fig. 1, A represents an auxiliary turbine of the condensing 90 plant, which, as shown, is employed to drive a mixed air and water pump J. The wheel chamber A' in which the turbine wheel B works, receives motive fluid from an injector C, which comprises compression nozzles D, expanding nozzles E', and a mixing chamber C' into which the expanding nozzles E' open and from which the compression nozzles D lead directly to the wheel chamber A'. A steam supply pipe F leading from a suitable source supplies steam to the nozzles E', and the mixing chamber C' is connected by the piping G to the air outlet, or preferably as shown to the distributed air outlets H' of the main condenser H. 100 The outlet chamber A² of the turbine is connected by the pipe I' to the auxiliary condenser I and the common air and water outlet from the latter is connected by the pipe I² to the inlet of the wet vacuum pump J, 110

which discharges into the hot well K. The nozzles E' are arranged to expand the steam supplied by the pipe F to the low pressure which it is desired to maintain at the air outlets of the main condenser, and the nozzles D recompress the mixture of steam and air passing through them to the higher pressure which it is desired to maintain in the auxiliary condenser I. By proceeding in this manner it will be seen that we utilize portions of the kinetic energy of the steam expanded in the nozzles E' to raise the pressure of the steam and air mixture, to rotate the turbine wheel, and to carry the mixture through the piping and into the auxiliary condensing and vacuum producing apparatus. The increased pressure maintained in the auxiliary condensing and vacuum producing apparatus results in a decreased volume of air and steam to be handled, thus permitting the use of a smaller air pump. The increased temperature of the mixture permits the cooling water to be discharged from the auxiliary condenser at a higher temperature than would otherwise be allowable and this is an advantage. The decreased volume and increased temperature of the mixture passed into the auxiliary condenser reduces the size and increases the efficiency of the auxiliary condenser. The steam supplied by the pipe F may be at low pressure; for instance, it may be bled from an intermediate stage of the turbine exhausting into the main condenser H. H² is the water outlet from the latter.

In the modified construction shown in Fig. 2, the steam supply pipe F for the turbine A¹ is directly connected to the steam chest A⁴ of the latter, so that the pressure in the steam chest is the same as in the pipe F. The steam chest A⁴ is connected to the wheel chamber A¹⁰ by expanding nozzles A⁶, and the pipe G leading from the air outlet or outlets of the main condenser is also connected to the turbine wheel chamber A¹⁰, which is of appreciably greater thickness than the turbine wheel BB working therein. In this form of our apparatus the wheel chamber A¹⁰ is connected to the exhaust chamber A²⁰ of the turbine by nozzles or passages A⁸, shaped to recompress the fluid passing through these passages to the desired extent. From the chamber A²⁰ the air and steam mixture may pass through the pipe I¹⁰ to auxiliary condensing and vacuum producing apparatus, as shown in Fig. 1. In this form of our invention the rejected velocity of the air and steam mixture as it leaves the turbine wheel is utilized in the desired recompression of the mixture. This rejected velocity is always substantial in the case of a small turbine of the type employed for auxiliaries.

In Fig. 2 the turbine wheel chamber A¹⁰ forms the mixing chamber of a sort of an

ejector of which the passages A⁵ and A⁶ form the expansion and compression nozzles. The turbine wheel itself forms an effective device for mixing the air and steam.

In the highly compact form in which our invention is embodied in Figs. 3 and 4, the auxiliary condensing and vacuum producing apparatus comprises a rotary jet condenser mounted in the same casing L as the turbine wheel BC by which it is driven. Steam is supplied through the pipe F to the arc shaped steam chamber L' which opens to the wheel chamber L² through expanding nozzles L³. The pipe G from the air outlets of the main condenser (not shown) opens to a chamber L⁴. The chamber L⁴ is directly open to the wheel chamber beneath the steam chamber. The mixture of air and steam issues from the wheel chamber L² through compression nozzle L⁶ which open at their discharge ends into the wheel chamber L' of a rotary jet condenser and air pump. The rotary impeller M of the latter is connected to and driven by the shaft B' of the turbine wheel BC. Q represents the condensing and hurling water supply pipe and L⁸ the diffusion chamber surrounding the impeller. In addition to its mechanical simplicity and compactness, the apparatus shown in Figs. 3 and 4 has the advantage of reducing the loss due to the frictional resistance to the flow of the fluids through the auxiliary condensing and vacuum producing apparatus by shortening the path traveled by these fluids.

Certain features of invention pertaining to the utilization of the kinetic energy of a portion of a body of steam to perform the mechanical work in the condensing apparatus required for the proper condensation thereof of this portion of the steam and also of another portion of said body of steam, disclosed but not claimed herein, is the sole invention of one of us; namely, Paul A. Bancel, and is claimed in application Serial No. 734,050 filed by him of even date herewith.

While in accordance with the provisions of the statutes we have illustrated and described the best forms of our invention now known to us, it will be apparent to those skilled in the art that changes may be made in the form of the apparatus disclosed without departing from the spirit of our invention, and that in some cases certain features of our invention may be employed without a corresponding use of other features.

Having now described our invention, what we claim as new and desire to secure by Letters Patent, is:

1. In a condensing plant, the combination of a main condenser, auxiliary condensing and vacuum producing apparatus, an auxiliary turbine wheel, a connection supplying

steam for driving said wheel, means for expanding said steam to a pressure not exceeding that which it is desired to maintain in said condenser, and means for utilizing a portion of the kinetic energy of the expanded steam to draw air out of said condenser and mix it with the steam and to recompress said mixture and deliver it to said apparatus at a pressure exceeding that maintained in said condenser.

2. In a condensing plant comprising a main condenser, and an auxiliary condensing and vacuum producing apparatus, the combination of a steam ejector adapted to withdraw air from said main condenser and means for compressing the mixture of air and steam issuing from the ejector, and delivering it to said apparatus at a pressure above that maintained in the main condenser, and a turbine wheel acted upon by and receiving energy from the mixture of air and steam.

3. In a condensing plant, the combination of a main condenser, having separate air and water outlets, auxiliary condensing and vacuum producing apparatus, an auxiliary steam turbine comprising a wheel chamber and a wheel working therein, means for supplying steam of low pressure and at high velocity to said chamber, an outlet connection leading from said chamber to said apparatus said connection being adapted to recompress the fluid passing through it, and a connection between said wheel chamber and the air outlet or outlets of said main condenser.

4. In a condensing plant, the combination of a main condenser, having separate air and water outlets, a rotary jet condenser

comprising an impeller chamber and a rotary impeller working therein, a turbine wheel chamber and a wheel working therein and connected to and driving said impeller, a hurling water supply connection for said impeller, a steam supply connection opening to said wheel chamber through one or more expanding nozzles, a connection between said wheel chamber and the air outlet or outlets of said main condenser, and an outlet connection from said wheel chamber to said impeller chamber, including one or more compression nozzles, whereby a pressure may be maintained in said wheel chamber corresponding to the vacuum desired in the main condenser, and the air and steam passing through said wheel chamber is delivered to said impeller at a pressure above that existing in said main condenser.

5. The combination with a chamber to be exhausted of means for withdrawing air therefrom comprising auxiliary condensing and vacuum producing apparatus, an auxiliary turbine wheel, a connection supplying steam for driving said wheel, means for expanding said steam to a pressure not exceeding that which it is desired to maintain in said chamber, and means for utilizing a portion of the kinetic energy of the expanded steam to draw air out of said chamber and mix it with the steam and to recompress said mixture and deliver it to said apparatus at a pressure exceeding that maintained in said chamber.
